United States Patent Office.

JOHN ROBBINS, OF CENTRALIA, ILLINOIS.

Letters Patent No. 94,914, dated September 14, 1869.

IMPROVED CLOTHES-LINE HOLDER.

The Schedule referred to in these Letters Patent and making part of the same.

To all whom it may concern:

Be it known that I, JOHN ROBBINS, of Centralia, in the county of Marion, and State of Illinois, have invented a new and valuable Improvement in Clothes-Line Holders; and I do hereby declare that the following is a full, clear, and exact description of the construction and operation of the same; reference being had to the annexed drawings, making a part of this specification, and to the letters and figures of reference marked thereon.

Figure 1, of the drawings, is a vertical section of my invention, showing its action in securing a line.

Figure 2 is a side view of same, showing method of tightening the line.

Figure 3 is a rear view, showing jaw B and loop.

My invention relates to a means for securing and tightening clothes-lines, and consists, mainly, in the construction and novel arrangement of a pair of metal jaws, so hinged together that when the line is pulled in one direction it slides easily, and when pulled at the other end it is firmly held.

The letter A, of the drawings, designates one of the jaws, having wings, to keep the line in place, and a

loop, I, at its upper end, through which the line passes for use, as at E.

The letter B designates the other jaw, having smaller wings, b, which are pivoted to the wings or cheeks A by the rivets or pins c.

The jaw B has also, at its upper end, a loop, H, similar to that of the jaw A, but used for fastening the device to the wall or post, by means of a supplementary rope, D.

This device will also prove useful in securing and tightening the cordage of vessels.

What I claim as my invention, and desire to secure by Letters Patent, is—

The device herein described, having jaws A and B, loops H and I, and rivets or pins c c, constructed, arranged, and operated substantially as specified.

In testimony that I claim the above, I have hereunto subscribed my name, in the presence of two witnesses.

JOHN ROBBINS.
